UNITED STATES PATENT OFFICE.

AUGUSTUS A. YERKES, OF PHILADELPHIA, PENNSYLVANIA.

APPARATUS FOR COLORING PAPER.

SPECIFICATION forming part of Letters Patent No. 395,257, dated December 25, 1888.

Application filed September 24, 1887. Serial No. 250,539. (No model.)

To all whom it may concern:

Be it known that I, AUGUSTUS A. YERKES, a citizen of the United States, and a resident of Philadelphia, Pennsylvania, have invented 5 an Improved Apparatus for Coloring Paper, of which the following is a specification.

My invention is designed principally for the production or manufacture of wall-paper; but it may also be used for the production or 10 manufacture of other papers or fabrics which have to be colored on one or both sides.

My invention is more especially useful for "grounding" wall-paper—that is, applying a ground or body color to one side of the web 15 of paper which is to be used for wall-paper. Under ordinary circumstances this grounding of the wall-paper is done in the wall-paper factory after the paper has come from the paper-mill; but the grounding of the paper 20 in the wall-paper factory is somewhat expensive, owing chiefly to the time and large space required for the drying of the color applied to the paper. In order to ground the paper in a more economical manner, I provide 25 the ordinary paper-making machine with an attachment by which the ground color may be applied to the web of paper as it is passing over the drying-cylinders, and the drying of the color is accomplished simultaneously 30 with the drying of the web of paper in the paper-making machine. By this means the separate drying appliances and the long space occupied by them in the wall-paper factory are dispensed with and time and labor economized. 35

It has been heretofore proposed to employ coloring devices in connection with the drying-cylinders of a paper-making machine; but the coloring devices proposed have not 40 been of a character practically available for the grounding of wall-paper, because the said devices would not give that even and uniform distribution of the color which is absolutely necessary in applying the ground or body 45 color to wall-paper.

In the accompanying drawings, Figure 1 is a side elevation of the drying-cylinders of an ordinary paper-making machine provided with my improvements, there being illustrated 50 in connection with the drying-cylinders pressing and calendering rolls and the cutting or slitting machine. Fig. 2 is a side

elevation, partly in section, of a portion of the drying-cylinders with my improvements applied thereto. Fig. 3 is a plan view of the 55 same; and Fig. 4 is a transverse section on the line 1 2, Fig. 3.

A is the frame of the paper-making machine, and B B are the drying-cylinders around which the sheet or web of paper a passes as 60 guided by the endless apron or blanket b in the usual manner. At a suitable point in the traverse of the paper I introduce my coloring appliances, and in the present instance I have shown these appliances as arranged 65 over the drying-cylinders so that the sheet of paper, instead of passing directly to the fifth cylinder from the fourth, first passes to the coloring appliances and then returns to the remaining drying-cylinders of the series 70 to complete the drying of the paper simultaneously with the drying of the applied color. As illustrated more fully in Figs. 2, 3, and 4, these coloring devices are carried by a frame or side frames, D, which may be removably mounted on the side frames of the drying-cylinders. On these frames D is mounted 75 a coloring table or surface, E, having at opposite ends rollers e, over which passes an endless blanket, e'. Above the front end of 80 this table is mounted an elongated transverse color-box, T, preferably closed at the top by a movable lid, f. Along the under side of the trough is a row of outlet-openings or, preferably, spouts, f', which may be closed by a 85 valve or valves, v, Figs. 3 and 4. Immediately underneath these spouts or other outlets is arranged a transverse rotary brush, G, which is adapted to rotate with its under side 90 in contact, or nearly so, with the paper as the latter passes over the coloring-table.

Within the color-box is a rotary stirring brush or paddle, d, to keep the color uniformly distributed throughout the box. At points along the length of the table are arranged transverse reciprocating brushes H, for 95 the proper distribution of the color which has been thrown onto the paper by the distributing-brush G. Motion may be applied to these several brushes by any suitable means and 100 in the present instance I have shown the rotary brushes as driven by pinions from the gear-wheels of the drying-cylinders.

The reciprocating brushes are driven by

eccentrics h on a shaft, h' , to which rotary motion may be transmitted by bevel-gearing or otherwise from the gear-wheels of the drying-cylinders. By preference the several reciprocating brushes are caused to move at speeds differing from each other by making the eccentrics h of different sizes.

Following on the coloring table or surface, and as a continuation thereof, is a heating-surface composed of heating-pipes within an endless belt or apron, J , passing around suitable rollers, J' , mounted in suitable bearings in the frames D . In the space left between the bottom and the top line of this apron are the heating-coils K .

The operation of these devices is as follows: The web of paper, as it leaves the fourth cylinder B , partially dried, passes from its guide-roller 2 to the coloring-table and under the coloring-brush G , which distributes the color as it comes from the color-box in a more or less uniform layer over the paper. The paper with the color thus applied then passes beneath the reciprocating brushes H , which lay the color perfectly even to produce a uniform shade or tint over the entire surface of the paper. The paper then passes over the heating-surface formed by the pipes K within the endless apron J , and thence back along the under side of the heating-surface to the tension-roller M , which is so mounted in the frame that it may be adjusted at either end to get the proper tension on the web of paper to avoid the formation of wrinkles or creases. The paper thence returns to the drying-cylinders of the machine. In the present instance I have illustrated the paper as returning to the sixth drying-cylinder B , thus omitting the fifth cylinder; but, if desired, the paper may be returned to the fifth cylinder, or, in other words, to that cylinder which immediately succeeds the cylinder from which the paper passes to the coloring appliances.

By the time the paper, colored as described, reaches the drying-cylinder, to which it is returned, the sizing in the color will have become set sufficiently by the heat from the coils K to prevent the color from being offset onto the succeeding drying-cylinders, which complete the drying of both the color and the paper as the web passes around them.

As will be seen on reference to Fig. 1, the web of paper passes from the drying-cylinders, as usual, to the pressing-rolls R , and thence to the calender-rolls P .

By suitably preparing the color the paper will be so polished by the calendering-rolls as to produce the satin finish for which heretofore a separate polishing-machine has been employed.

In connection with the machine as provided with my coloring appliances I may use the cutting or slitting machine S , whose cutters are adjusted to trim off the edges of the paper, and also to cut the paper longitudinally, if double width is made. By this means the roll of paper as it leaves the cylinder is not only "grounded," but is also trimmed at the edges, so that it may be hung on the walls without further trimming by the wall-paper manufacturer or paper-hanger.

I claim as my invention—

1. The combination of the drying-cylinders of a paper-making machine with a coloring table or surface, the liquid-color-supply trough having valved outlets, a rotary brush immediately under the latter, and additional color-distributing brushes, substantially as described.

2. The combination of the drying-cylinders of a paper-making machine with a coloring table or surface, a liquid-color-supply trough having valved outlets, a rotary distributing-brush immediately below the latter, and reciprocating brushes over the coloring-surface, substantially as specified.

3. The combination of the drying-cylinders of a paper-making machine with a coloring table or surface, a color-trough having a row of valved outlets, a rotary distributing-brush beneath the latter, and transverse reciprocating brushes over the coloring-surface, substantially as described.

4. The combination of the drying-cylinders of a paper-making machine with coloring appliances and a heating-surface between the coloring appliances and the drying-cylinders, to which the colored paper is to pass, all substantially as described.

5. The combination of the drying-cylinders of a paper-making machine with a coloring-table and color-distributing brushes and heating-pipes above and below which the web of paper passes from the coloring appliances to the drying-cylinders, all substantially as described.

6. The combination of the drying-cylinders of a paper-making machine, a coloring-table, an endless apron passing over the same, and color-distributing brushes with heating-coils, an endless apron passing around the coils, and a tension-roller, all substantially as set forth.

In testimony whereof I have signed my name to this specification in the presence of two subscribing witnesses.

AUGUSTUS A. YERKES.
